UNITED STATES PATENT OFFICE.

GEORGE B. McBEAN, OF HIGHLAND PARK, ILLINOIS, ASSIGNOR TO MECHANICAL & ELECTRICAL MANUFACTURING COMPANY, OF CHICAGO, ILLINOIS, A CORPORATION OF ILLINOIS.

SIGNAL LAMP.

Application filed January 29, 1917. Serial No. 145,217.

To all whom it may concern:

Be it known that I, GEORGE B. McBEAN, a citizen of the United States, and resident of Highland Park, in the county of Lake and State of Illinois, have invented a new and useful Signal Lamp, of which the following is a specification.

This invention relates to signal lamps and relates particularly to signal lamps for indicating the direction of travel of a vehicle, particularly for signalling a contemplated change in the direction of travel of such vehicle.

The object of the invention is to provide a signal lamp for the purpose specified which shall be simple in construction, relatively cheap to manufacture, and effective for its designed purpose. To this end, a signal lamp of my invention comprises the various features, combinations of features and details of construction hereinafter described and claimed.

In the accompanying drawings, in which my invention is fully illustrated,

Figure 1 is a sectional side view of my improved signal lamp and operating mechanism therefor, the section being taken on the line 1—1 of Fig. 2.

Figure 2 is a top plan view of my improved signal lamp and operating mechanism therefor, showing the operating mechanism in plan section on the line 2—2 of Fig. 1.

Figure 3 is a view of the operating mechanism from the position 3—3 of Fig. 2.

Figures 4, 5, 6, 7 and 8 are different views, on a reduced scale, from the position 4—4 of Fig. 2, Figs. 4, 5, 7 and 8 showing different shutters in closed position to display different signals, and Fig. 6 showing all of said shutters open.

Figure 9 is a front view of a signal lamp embodying my invention in modified form.

Figure 10 is a sectional side view thereof, the section being taken on the line 10—10 of Fig. 9.

Fig. 11 is a sectional elevation thereof on the line 11—11 of Fig. 10.

Figure 12 is a side view of a signal lamp embodying another modification of my invention.

Figure 13 is a front view thereof; and Figure 14 is a sectional end view thereof on the line 14—14 of Fig. 12.

As shown in the drawings, the lamp, designated A, forming part of my improved signalling apparatus, is assumed to be the usual tail lamp of an automobile or other vehicle. As shown, said lamp is indicated as being an electric lamp, but my invention contemplates equally the use of an oil lamp.

Said lamp A may be any usual form of commercial signal lamp commonly used on motor vehicles of various kinds at the present time and is adapted to be mounted on the vehicle in any usual and well known manner. Also, the electrical connections for said lamp whereby said lamp may be controlled by the driver of the car can be readily supplied by any electrician of ordinary skill without any description thereof, and such connections are not, therefor, shown in the drawings.

To effect the objects of the invention as it relates to signalling the contemplated direction of travel, the light opening a of said lamp A is controlled by means of different shutters made of suitable opaque material, preferably thin sheet metal, formed in which, respectively, are openings shaped to form pointers—preferably arrows—indicating different directions.

While my invention contemplates the use of any desired or approved form of shutters, I prefer the form of shutter used very largely on photographic cameras and generally known as diaphragm shutters. Shutters of this type are old and well known and can readily be constructed and supplied by persons familiar with camera construction without a description in detail thereof. Said shutters, which are separately shown in closed positions in Figs. 4, 5, 7 and 8 are designated, respectively, 1, 2, 3 and 4, and the pointers or arrows formed in said shutters, respectively, 1', 2', 3' and 4'.

Said shutters are operatively mounted in a casing B supported in front of the light opening a of the lamp A, provided in its front and back walls with openings for the passage of the light from the lamp A, glass plates 5 and 6 being secured in said open-

ings, respectively. In the case of the tail lamp of a motor vehicle, one of said plates, preferably the inner plate 5, is red, while the outer plate 6 is preferably clear and is designed primarily to protect said shutters and the actuating mechanism therefor mounted in the casing B and to prevent access of dust, dirt and the like thereto.

As shown, said shutter casing B is supported at the outer end of an extension b of the tubular projection a' which defines the light opening a of the lamp A. Also, to provide for the use of arrows of such size that they may be readily and clearly seen at such distance as will render them effective, said shutter casing and shutters are made relatively large, the sides of said extension b of the lamp casing being correspondingly flared so that the outer end 20 thereof to which said casing B is attached shall be larger than the light openings 5 and 6 through said shutter casing.

In accordance with my invention, I contemplate operating the shutters 1, 2, 3 and 4 either mechanically, pneumatically or in any other desired or approved manner, said shutter mechanism being so constructed and arranged that said shutters will be normally open so that they will not obstruct the light 30 from the lamp A and are adapted to be closed separately when it is desired to display the signals defined thereby, respectively. Shutters of this type adapted to be operated in the manner specified are old and well known in shutter construction for cameras and can readily be constructed and supplied by persons familiar therewith without a detailed description thereof.

As indicated in the drawings, said shutters 40 are adapted to be operated mechanically by means of usual trip levers 7, 8, 9 and 10 constructed and arranged to separately close the shutters 1, 2, 3 and 4, respectively.

Pivotal movement to close the shutters is 45 adapted to be imparted to the trip levers 7, 8, 9 and 10 by suitable operating means mounted on the car—as on the steering post or dash—in position to be conveniently accessible to the driver of the car.

50 As shown, the parts of said operating mechanism are mounted on a suitable framework, consisting of a casing 11, one end of which is closed by a removable cover plate 12 to provide access to the interior thereof 55 and the parts enclosed thereby, and comprise bell-crank levers 7', 8', 9' and 10' mounted to turn freely on a rod 13 secured against rotation in suitable bearings in the side walls of the casing 11. The trip levers 60 7, 8, 9 and 10 and the bell crank levers 7', 8', 9' and 10' are operatively connected in such manner that pivotal movement of said bell crank levers in one direction will impart pivotal movement to the shutter trip levers in a direction to close said shutters

and, in the opposite direction, will permit said trip levers to be returned to their normal positions corresponding to open positions of said shutters. As shown, the arms 7², 8² and 10² of said bell crank levers are 70 connected to the shutter trip levers 7, 8, 9 and 10 by flexible wires or the like designated 7³, 8³, 9³ and 10³, respectively, which, as shown, pass around idle pulleys 14 and 15 75 rotatably mounted in suitable position on the frame of the vehicle, preferably in such position that the end sections of said connecting cables will extend substantially vertically from their points of attachment to said trip levers and bell crank levers. 80

Pivotal movement is adapted to be imparted to the bell crank levers 7', 8', 9' and 10', respectively, by means of rods or plungers 7⁴, 8⁴, 9⁴ and 10⁴ mounted so as to be freely movable endwise in suitable bearings formed in the casing 11. As shown, the bearings for said rods or plungers are formed in the bottom wall 16 of a recess 17 formed in the removable front wall 12 of the casing 11, and in a plate 18 secured in the open side 90 of said recess.

The inner ends of said plungers 7⁴, 8⁴, 9⁴ and 10⁴ are slotted to receive the arms 7⁵, 8⁵, 9⁵ and 10⁵ of the bell-crank levers and said plungers and bell-crank levers are connected by pins 19 on said plungers which extend through slots 20 formed in the arms 7⁵, 8⁵, 9⁵ and 10⁵ of said bell-crank levers, the relation being such that endwise movement of said rods or plungers in opposite direction will impart desired pivotal movement to said bell-crank levers to open and close the shutters 1, 2, 3 and 4. 100

Said plungers are adapted to be maintained at the inner limit of their movement, 105 corresponding to open position of the shutters 1, 2, 3 and 4, by means of springs applied thereto consisting, as shown, of coiled springs 21 inserted between the bearing plate 18 and lateral projections 22 on said rods or plungers and which surround said rods or plungers as guides. As shown, said projections 22 consist of pins secured in said rods or plungers and which project laterally therefrom. 110

Necessary pivotal movement to release the shutters 1, 2, 3 and 4 is adapted to be imparted to the trip levers 7, 8, 9 and 10 by pivotal movement of the bell-crank levers 7', 8', 9', and 10' produced by pulling out the plungers 7⁴, 8⁴, 9⁴, and 10⁴ against the force of the springs 21 applied thereto, and said plungers and associated parts are adapted to be secured or locked in such retracted position by means of a suitable detent or detents applied thereto. As shown, said detent consists of a transverse bar 23 supported at the upper ends of arms 24 pivoted on a transverse rod 25 the ends of which are secured 120 in bearings in the side walls of the casing 11. 125

Said detent 23 is adapted to engage shoulders 26 formed on short lugs or projections 27, on the under sides of the rods or plungers 7⁴, 8⁴, 9⁴ and 10⁴ the front sides of said lugs or projections, by contact with the detent 23, operating to impart pivotal movement to said detent as said rods or plungers are pulled out or retracted to permit engagement of said detent with said shoulders 26.

10 The detent is returned to locking position by means of springs 28 applied to the lower ends of the arms 24, and the locking position of said detent is defined by means of a stop pin 29 which projects into the path of travel 15 of one of the arms 24.

In the preferable construction shown, also, all of said rods or plungers, when locked in retracted or pulled out positions by the detent 23, are adapted to be released 20 and returned to normal positions by the springs 21 applied thereto, thereby opening the shutter controlled by said retracted or pulled out plunger or plungers, by the re- 25 tracting or pulling out of any of said rods or plungers to close the shutter controlled thereby. This is effected by employing a common detent or detents for all of said rods or plungers whereby, as said detent is moved pivotally by the retraction of any of 30 said rods or plungers to effect engagement of said detent with the shoulder on said rod or plunger thus pulled out, the pivotal movement thus imparted to said detent will effect disengagement thereof with the shoul- 35 der 26 on any rod or plunger held in re- tracted or pulled out position thereby, thus permitting said retracted or pulled out plunger or plungers to be returned to normal position by the springs 21.

40 In addition to the plungers 7⁴, 8⁴, 9⁴ and 10⁴ for controlling and operating the shutter trip levers 7, 8, 9 and 10, I provide an additional rod or plunger designated 31 which is designed merely for releasing the other rods or plungers which control the shutter trip levers so as to open all of the shutters, when the vehicle is running straight ahead, and fully expose the tail or other lamp. To this end, said rod or plunger 31 has no connection with any of the shutter trip levers 7, 8, 9 and 10, but has on its under side a projection provided with a shoulder substantially similar to the projection 27 and the shoulders 26 formed on the other rods or plungers. Thus, as said rod or plunger 31 is retracted or pulled out, any of the rods or plungers 7⁴, 8⁴, 9⁴ and 10⁴ which may be secured in retracted or pulled out position will be released and returned to normal position by the springs 21, which will open all 55 of the shutters.

To adapt my improved signal lamp for use both at night and in the day time, the exposed sides of the shutters will be colored 60 to contrast with the light. Thus, in the case

of a tail lamp, which is red, the exposed sides of the shutters are colored white, while in the case of head lights, which are white, the exposed sides of said shutters will be colored black.

In use, when the vehicle is running straight ahead, all of the shutters will be open and the light opening of the lamp unobstructed, as shown in Fig. 6; thus fully exposing the light therefrom. When the driver contemplates turning to the right, he pulls out or retracts the rod or plunger 7⁴, thereby closing the shutter 1 and displaying the arrow 1' formed therein, which points to the right and indicates to others 70 that he contemplates turning to the right. When the driver contemplates turning to the left, he pulls out the rod or plunger 8⁴, which closes the shutter 2 and displays 75 the arrow 2' formed therein, which points to the left and indicates to others that he contemplates turning to the left. When standing still and he contemplates going ahead when he starts, he pulls out the rod or plunger 9⁴ which closes the shutter 3 and displays 80 the arrow 3' formed therein, which points upwards and, by accepted convention, indicates that he intends going ahead. And when he contemplates backing up, he pulls out the rod or plunger 10⁴, which will 85 close the shutter 4 and display the arrow 4', which points downward and, by accepted convention, indicates that he intends to back up.

Also, when the driver contemplates driving ahead for any considerable distance without turning, he pulls out the rod or plunger 31, which, as previously explained, will open any closed shutter and expose the 90 full light opening of said lamp.

As explained, also, when any rod or plunger is pulled any other rod or plunger which may be locked in pulled out position, will be released and will permit the shutter controlled thereby to open, thus effectually preventing obscuring and confusion of the different signals.

For convenience, the rods or plungers which control different shutters or perform different functions are preferably appropriately marked. Thus, on the outer end of the plunger 7⁴ an arrow pointing down and the word "Back" will appear; on the end of the rod or plunger 8⁴ an arrow pointing up and the word "Ahead"; on the plunger 9⁴ an arrow pointing to the left and the word "Left"; on the plunger 10⁴ an arrow pointing to the right and the word "Right"; and on the plunger 31, the word "Neutral".

Instead of the particular form of shutter specified, my invention contemplates the use of other forms of shutters. For example, I contemplate the use of shutters each consisting of a plate of suitable material, preferably sheet metal, pivotally mounted at dif- 125

ferent sides of the light opening of the lamp casing in such position that pivotal movement thereof in different directions will respectively obscure and expose the lamp proper.

- This modification is shown in Figs. 9 to 11 of the drawings, in which A' designates the lamp proper, a² the light opening defined by a tubular extension b' of the lamp casing, said extension preferably comprising a flared portion b² and an outer rectangular portion b³. Pivoted to different sides of the rectangular portion b³ of said extension are shutters 1², 2², 3² and 4², formed in which, respectively, are holes or openings which define pointers indicating different directions, preferably in the form of arrows, designated, respectively, 1³, 2³, 3³ and 4³. Said shutters are maintained normally open by means of springs applied thereto, as coiled springs 32 applied to the pivots thereof and are adapted to be closed, when desired, to obscure the lamp A' by suitable means mounted in position to be conveniently accessible to the driver of the vehicle and which preferably comprise means for securing said shutters in closed positions and for releasing them to permit them to open, said releasing means preferably comprising means controlled by operation of the mechanism for closing any open shutter and also separate means common to all of said shutters, whereby in running straight ahead, any closed shutter may be released so as to permit the same to open and thus fully expose the lamp. For operating said shutters, the operating means shown in Figs. 1 and 2 and heretofore described, may be used without change, by attaching the cords or wires 7³, 8³, 9³ and 10³ to lever arms 33, 34, 35 and 36 secured to the pivot pins of said shutters, respectively, the relation being such that said shutters will be closed by pulling out the plungers applied thereto, respectively, and any closed shutter may be released and permitted to open by pulling out the plunger for closing any open shutter and also by pulling out the neutral plunger 31.
- A glass plate 37 is preferably secured in the extension b' of the lamp casing, which may be red or clear depending upon the purpose for which it is intended. As shown, said plate is secured in said extension b' outside of said shutters so as to exclude dust, dirt and the like therefrom.

Instead of forming the different pointers on separate shutters, I contemplate, as a further modification of my invention, a construction in which all of said pointers are formed in a single shutter.

This modification is shown in Figs. 12 to 14 of the drawings, in which A² designates the lamp proper, a³ the light opening in the lamp casing defined by a tubular exten-

sion b⁴ of said lamp casing. Slidably mounted in suitable transverse guides so as to be freely movable endwise therein in both directions, is a shutter 38, preferably made of sheet steel or other suitable metal, formed in which are holes or openings 1⁴, 2⁴, 3⁴ and 4⁴ which define pointers, as arrows, which indicate different directions, and an opening 39 registration of which with the light opening a³ will effect full exposure of said lamp.

Endwise movement is adapted to be imparted to said shutter 38 by suitable operating mechanism provided for the purpose so located as to be conveniently accessible for operation by the driver of the vehicle. Simple means for this purpose are as follows:—Applied to said shutter is a spring 40 adapted for maintaining the same normally at one limit of its movement, which preferably corresponds to register of the opening 1⁴ therein with the light opening a³.

Movement against the force of said spring to bring the different openings 2⁴, 3⁴, 4⁴ and the light opening 39 into register with said light opening a³, is adapted to be imparted to said shutter against the force of the spring 40 applied thereto, by a lever 41 mounted on the dash or on the steering post of the vehicle, not shown, so as to be conveniently accessible to the driver of the vehicle, which is connected by a cord or wire 42 with the end of the shutter 38 other than that to which the spring 40 is connected. The positions of the lever 41 to bring the different pointers or arrows defined by the openings 1⁴, 2⁴, 3⁴ and 4⁴ in register with the light opening of the lamp is defined by suitable stops, consisting of a spring pressed bolt 43 mounted on the lever 41 which is adapted to engage notches 44, 45, 46, 47 and 48 in a segment 49, said notches and the end of said bolt being V-shaped, thus forming a spring catch which will engage automatically and may be disengaged by a push or pull on said lever.

The notches 44, 45, 46, 47 and 48 may be appropriately marked, as with the letters N., R., L., A. and B., respectively, being the first letters of the words "neutral", "right", "left", "ahead" and "back", and the relation being such that when in engagement with said notches, respectively, the arrows or pointers indicating the directions of travel indicated by the letters applied thereto will be displayed.

The signal lamp last described differs from the other two in the respect that it is not automatic and when a signal is once displayed it will remain so until the lever is again moved into a different position. For this reason, I consider this form of signal lamp less desirable than the other two, although it is in all respects practical.

I claim:—

1. Signaling apparatus for vehicles comprising a plurality of signals for indicating different directions of travel, means for displaying said signals separately and means for obscuring any displayed signal rendered operative by actuation of the means for displaying any obscured signal and constructed and arranged for maintaining said signal obscured until the means for displaying same is again operated.

2. Signalling apparatus for vehicles comprising a plurality of signals for indicating different directions of travel, means for displaying said signals separately, means for obscuring any displayed signal rendered operative by actuation of the means for displaying any obscured signal, and separate means common to all of said signal obscuring means for rendering the same operative.

3. A signal lamp comprising a casing, a plurality of diaphragm shutters mounted therein in fixed axial alignment so as to define a single light opening controlled by said shutters and designed to be normally unobstructed, said shutters, respectively, being provided with means for indicating different directions of travel, and means for operating said shutters to display and obscure said indicating means.

4. A signal lamp comprising a casing provided with a light opening, a plurality of shutters for covering and uncovering said light opening, said shutters being provided with means indicating different directions, means for closing said shutters separately, and means for opening any closed shutter rendered operative by actuation of the means for closing any open shutter.

5. A signal lamp comprising a casing provided with a light opening, a plurality of shutters for covering and uncovering said light opening, said shutters being provided with means indicating different directions, means for closing said shutters separately, means for opening any closed shutter rendered operative by actuation of the means for closing any open shutter, and separate means common to all of said shutter opening means for rendering the same operative.

6. A signal lamp comprising a casing provided with a light opening, a plurality of shutters for covering and uncovering said light opening, said shutters being provided with means indicating different directions, means for maintaining said shutters normally open, means for closing said shutters separately and for securing them in closed position, constructed and arranged for simultaneously releasing any closed shutter.

7. A signal lamp comprising a casing

8. A signal lamp comprising a lamp proper of the bull's-eye type provided with a light opening, the casing of said lamp comprising an extension which surrounds said light opening, a plurality of shutters mounted in the extension of said lamp casing adapted for covering and uncovering said light opening, said shutters being provided with openings which define pointers indicating different directions, means for closing said shutters separately, and means for opening said shutters controlled by the means for closing any open shutter.

9. A signal lamp comprising a lamp proper of the bull's-eye type provided with a light opening, the casing of said lamp comprising an extension which surrounds said light opening, a plurality of shutters mounted in the extension of said lamp casing adapted for covering and uncovering said light opening, said shutters being provided with openings which define pointers indicating different directions, means for closing said shutters separately, means for opening said shutters rendered operative by actuation of the means for closing any open shutter and separate means common to all of said shutter opening means for rendering said shutter opening means operative.

10. A signal lamp comprising a lamp proper of the bull's-eye type provided with a light opening, the casing of said lamp comprising an extension which surrounds said light opening, a plurality of shutters mounted in the extension of said lamp casing adapted for covering and uncovering said light opening, said shutters being provided with openings which define pointers indicating different directions, means for maintaining said shutters normally open, means for closing said shutters separately and for securing them in closed position, constructed and arranged for simultaneously releasing any closed shutter.

11. A signal lamp comprising a lamp proper of the bull's-eye type provided with a light opening, the casing of said lamp comprising an extension which surrounds said light opening, a plurality of shutters mounted in the extension of said lamp casing adapted for covering and uncovering said light opening said shutters being provided with openings which define pointers

6
indicating different directions, means for maintaining said shutters normally open, means for closing said shutters separately and for securing them in closed position, 5 constructed and arranged for simultaneously releasing any closed shutter, and separate means common to all of said shutter

opening means for releasing any closed shutter.

In testimony, that I claim the foregoing 10 as my invention, I affix my signature this 11th day of January A. D. 1917.

GEORGE B. McBEAN.
